UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

YARN-TWISTING APPARATUS.

No. 805,752.

Specification of Letters Patent.

Patented Nov. 28, 1905.

Application filed May 25, 1905. Serial No. 262,136.

To all whom it may concern:

Be it known that I, ALONZO E. RHOADES, a citizen of the United States, and a resident of Hopedale, county of Worcester, State of Massachusetts, have invented an Improvement in Yarn-Twisting Apparatus, of which the following description, in connection with the accompanying drawings, is a specification, like characters on the drawings representing like parts.

This invention relates to apparatus for twisting and forming a fancy yarn having bunches or enlargements thereon at intervals; and it has for its object the production of novel and simple means for making the desired product, as set forth.

In United States Patent No. 764,632, granted to me July 12, 1904, means are provided for making a fancy yarn with bunches of two or more different colors, a plurality of bunches being formed simultaneously upon the main yarn or core at each arrest thereof, both main and auxiliary yarns being delivered in continuous lengths.

In my present invention the fancy yarn is formed by binding or twisting in with a plurality of yarns a series of pieces or relatively short lengths of a relatively weak or readily-breakable soft and larger yarn or roving, meaning thereby a yarn so slack-twisted or having so little twist that it is practically or may, in fact, be "roving," as commonly known in the art. This is delivered in continuous form to the binder-yarns; but the delivery is intermittent, while the binder-yarns are delivered continuously to the twisting instrumentality. As a result, each arrest of delivery of the weaker yarn or roving causes a portion thereof to be broken off and bound in by and with the binder-yarns, forming a bunch, another bunch being started as soon as delivery of the bunch-forming yarn or roving is resumed and completed as before, when its delivery is again arrested. A very odd and fancy yarn can thus be produced with great rapidity, the bunches being firmly bound in with the binder-yarns, which latter may be of colors contrasting with each other and with the softer yarn or roving.

The various novel features of my invention will be fully described in the subjoined specification and particularly pointed out in the following claims.

Figure 1 is a front view, broken out near

one end, of a twisting apparatus embodying one form of my invention, one of the twister-spindles being partly shown with its base and attached whirl. Fig. 1^a is a sectional detail, to be referred to, on the line 1 1, Fig. 1, looking toward the left. Fig. 2 is a right-hand end elevation of the means for driving and controlling the operation of the intermittently-acting delivery-rolls for the bunch-forming yarn or roving. Fig. 3 is a transverse sectional detail on the line 3 3, Fig. 1, looking toward the right. Fig. 4 is an inner face view of the clutch-controller to be described. Fig. 5 is an inner face view of the two members of the clutch with which the controller co-operates. Fig. 6 is a longitudinal sectional detail taken through the center of the clutch, its controller, and some of the adjacent parts substantially on the line 6 6, Fig. 4. Fig. 7 is a sectional detail, to be referred to, on the line 7 7, Fig. 4; and Fig. 8 is a view showing a length of the bunch-yarn enlarged.

I have herein shown my invention embodied in a machine similar in general construction to twisting apparatus frequently employed for heavy yarns in order to hold the twist thereof; but the back set of rolls is shown as a double set and is intermittently driven, while the single front set of rolls is driven continuously to produce the bunch-yarn in accordance with my invention.

Referring to Fig. 1, twisting instrumentalities or spindles S, finger-boards a' on the guide-boards a and provided each with a guide-eye or pig-tail a^x, the head A at the left-hand side of the frame and containing usual mechanism for positively and continuously driving the front set of rolls f f', and the roll-stands D may be and are substantially of well-known and usual construction, except in certain particulars to be hereinafter referred to. The stands D support the roll-carriers D' for the top rolls of both the back and front sets of delivery-rolls, the lower front roll f being positively driven from the head motion and having its shaft f^x extended the length of the frame, the driving-gear A^x, Fig. 1, being secured to the left-hand end of the shaft. The top front rolls f' run loosely in bearings in the roll-carriers D' and are driven by frictional contact with the roll f. The binder-yarns b¹⁰, two being herein shown, are led down to the back of the front set of rolls and are separated and trav-

ersed by guide-bars g , suitably mounted on the traversed bar T , Fig. 3; but more than two binder-yarns may be used, if desired, said yarns passing between the rolls f f' and 5 thence through the pig-tails a^x to the twisting instrumentality.

I have herein shown the back set of rolls as a double set, the shafts of the lower rolls b b' at the left-hand end having fast thereon 10 pinions 1 and 2, which mesh with an intermediate 3, so that said rolls rotate in unison in the same direction by means to be described, the corresponding top rolls b^x b'^x rotating loosely in bearings in the roll-carriers 15 and being driven by frictional engagement with the lower rolls.

The bunch-forming member b^x , a soft, slack-twisted yarn or roving and usually having much more body or bulk than the binder-yarns and being relatively much weaker, so 20 as to be readily broken, is led to the nip of the rolls b b'^x by a trumpet t , as in Fig. 3, and thence forward between the rolls b b'^x to the front set of rolls, and when the back set 25 of rolls is in operation the bunch-forming yarn travels with the binder-yarns and is twisted with them as they leave the front rolls f f' .

When the back set of rolls is stopped, 30 delivery of the bunch-forming yarn or roving b^x is arrested and the pull or drag, due to the continuously-running front rolls, breaks the bunch-forming yarn between the front and back sets of rolls, the broken-off portion being twisted in or bound with the binder-yarns, 35 completing one end of a bunch.

Immediately upon resumption of delivery by the back set of rolls the leading end of the yarn or roving b^x will be caught by the binder-yarns and carried forward with them, and the 40 formation of another bunch is begun, the length of the bunch being determined by the duration of the delivery period of the intermittently-operating back set of rolls. By this 45 operation a bunch-yarn is formed of the general character shown in Fig. 8, the bunches being formed by the separated pieces of yarn or roving b^x , bound or twisted with the binder-yarns b^x . The longer the delivery periods of 50 the back set of rolls the longer will be the bunches, the intervals between bunches being longer or shorter as the rest periods of the back set of rolls are longer or shorter.

I will now describe the means for effecting 55 the intermittent operation of said set of rolls and for varying the length of the delivery periods thereof.

A pinion 4 is secured on the right-hand end of the lower front-roll shaft f^x in mesh with 60 a large gear 5, rotatably mounted on a stud 6, adjustably secured on a suitable stand 7, the gear 5 in turn meshing with a pinion 8. (See dotted lines, Fig. 2, and in section, Fig. 6.) This pinion is fixedly secured to the hub 9 of 65 a pawl-carrier, shown as a disk 10, loosely

mounted on the extended right-hand end of the shaft 11 of the lower roll b' of the back set of rolls, said shaft having an outer bearing at 12 in the stand 7. A pawl 13, fulcrumed at 14 on the pawl-carrier (see Fig. 5) and acted upon by a suitable spring 15, has an elongated tail 16, the pawl-carrier and pawl forming one member of a clutch and being loose relative to the shaft of the roll b' , the tail of the pawl being long enough to project beyond the periphery of the pawl-carrier, as in Fig. 5. The co-operating member of the clutch is shown as a ratchet 17, keyed to the shaft 11 to rotate therewith, so that it is fast with relation to the roll b' , the ratchet being placed adjacent the 70 face of the disk 10. (See Fig. 6.) The spring 15 serves to normally keep the pawl in engagement with the ratchet, and as the pinion 8 is continuously rotated through the gear 5 and pinion 4 the pawl-carrier is continuously 75 rotated, and so long as the pawl and ratchet are in engagement the roll b' and the roll b , geared therewith, as explained, will be rotated in unison, and the operation of the back set of rolls thereby effected to cause delivery of the 80 bunch-forming yarn or roving. When the members of the clutch are disengaged, however, the back set of rolls will be stopped and the delivery of the bunch-forming yarn or 85 roving will be stopped and the latter broken, 90 as previously described. Adjacent the bearing 12 a gear 18 is loosely mounted on the shaft 11, said gear having secured to it, by suitable screws 24, Fig. 6, a clutch-controller, shown as a disk 23, having an inturned peripheral flange 25, provided with an internal 95 annular shoulder 26. The flange is shown in Fig. 4 as radially thickened to present two diametrically opposite cam surfaces or risers 27, projecting inward in the path of the tail 100 105 110 115 120 125 130 135 140 145 ports a short rotatable shaft 34, having fast upon it at its outer end a pinion 35 in mesh with the gear 19, and at its inner end said shaft has secured to it a gear 36, in mesh with the pinion 4.

The pinion 35 and gear 36 constitute removable transmitting-gearing intermediate the actuating-pinion 4 and the gear 19, which drives the clutch-controller, and by introducing transmitting-gearing of different sizes the speed of rotation of the clutch-controller will be varied relatively to that of the pawl-carrier 10, the latter being driven from pinion 4 through gear 5 and pinion 8, as described previously, and as the said pinions are shown as of substantially the same diameter the pawl-carrier will be driven at virtually the speed of the roll-shaft f^x ; but the gearing intermediate the pinion 4 and the clutch-controller gear 18 is so constructed as to rotate the controller at a slower speed than the pinion 4 and the pawl-carrier, and consequently the pawl-tail will pass and be operated by one after another of the risers and segmental cams or shoes on the controller, as in my patent referred to. As in said patent, the engagement of the pawl-tail with a cam operates to withdraw the pawl from the other member of the clutch—viz., the ratchet 17—and thereby the back set of rolls is disconnected from the actuating means in the present apparatus, and delivery of the bunch-forming yarn or roving b^o is arrested and the latter broken, as has been described. The rest period continues until the tail of the pawl wipes over the longitudinal edge of the shoe 31 and drops off the end thereof, whereupon the spring 15, Fig. 5, immediately effects reengagement of the clutch members and rotation of the back set of rolls begins, so that the binder-yarns and the leading end of the bunch-forming yarn or roving begin the formation of a new bunch.

The position of the shoes 31 determines the spaces between bunches and also the length of the bunches, for by setting the shoes in toward the risers 27 the duration of the rest periods is shortened and the distance between bunches will be decreased, while the length of the bunch is correspondingly increased to conform to the distance between the end of one cam and the riser of the next one. If the cams are moved outward from the risers, the length of the bunches will be decreased, while the distance between bunches is increased.

Of course the differential speed between the pawl-carrier and the clutch-controller will have its effect on the length of bunch and distance between adjacent bunches.

By changing the clutch-controller for one having a different number of cams and varying the transmitting-gearing the distance between and length of bunches will be varied.

By removing the transmitting-gearing, as may be effected when the bolt 33 of the stand

32 is loosened, the actuating connection between the pinion 4 and the clutch-controller gear 18 is thrown out, and at such time the controller is held stationary by dropping a locking-pin 37 through a hole 19^x in the hub 70 of the gear 19 into the socket 22^x, (see Fig. 1^a,) thereby locking the gear and controller from rotation. The pawl then travels around within the fixedly-held clutch-controller, and the length of bunch and distance between bunches 75 will be controlled thereby, according to the adjustment of the cam-shoes and the speed of rotation of the pawl-carrier. The back set of rolls is adjustable toward and from the front set, this adjustment being effected in usual 80 manner to compensate for the varying lengths of staple in the different grades of roving used for the bunch-forming member b^o , the back set of rolls being moved forward for short staple, and for long staple the said rolls are 85 moved farther back, the roll-stands D being of usual construction to permit such adjustment. As the shaft 11 of the lower back roll b' partakes of this movement toward the back or front of the frame the bearing 12 for its 90 right-hand end must be adjustable, and for the purpose the stand 7 is vertically adjustable in the bracket 20 by means of the bolt 38, Fig. 2, which passes through a vertical slot 39 in the bracket 20, while the latter is adjustable fore and aft on the fixed stand 21 by bolts 40, passing through horizontal slots 41 in said stand. (See Fig. 2.) For a slight adjustment the gears 18 and 19 will remain in mesh; but for a greater adjustment the gear 19 must 100 be changed for one having the requisite pitch, necessitating a corresponding change in the pinion 35.

The arrows 42, Figs. 2 and 4, indicate the direction of rotation of the clutch-controller, 105 and the arrows 43 in Figs. 2 and 5 indicate the direction of rotation of the pawl-carrying member 10 of the clutch. The arrangement herein illustrated produces relatively small bunches close together, because the clutch and clutch-controller are rotated in opposite directions, (see the arrows 42 43, Fig. 2;) but by removing the transmitting-gearing 35 36 and locking the clutch-controller, as herein-before referred to, a much longer bunch will 115 be produced with longer intervals between bunches, for then the relative speed of clutch and clutch-controller is reduced, as will be manifest, as the clutch-controller is stationary.

Various changes or modifications in different details of construction and arrangement may be made by those skilled in the art without departing from the spirit and scope of my invention, one practical embodiment of which is herein shown and described.

Having fully described my invention, what I claim as new, and desire to secure by Letters Patent, is—

1. In apparatus of the class described, a twisting instrumentality, a front set of con- 130

tinuously-driven rolls to deliver thereto a plurality of binder-yarns to be twisted together, a back set of intermittently-driven rolls for a relatively weak yarn or roving, to deliver the latter intermittently to and to be twisted or bound with the binder-yarns, and adjustable means to vary the delivery periods of the intermittently-driven rolls, the bunch-forming portions passing through both sets of rolls 10 and being severed by arrest of the back set of rolls.

2. In apparatus of the class described, a front set of delivery-rolls, a back set of delivery-rolls adjacent thereto, continuously-15 running actuating means directly connected with the front set of rolls, a clutch intermediate said means and the back set of rolls, and comprising two coöperating members respectively fast and loose with relation to the back 20 set of rolls, the loose member being driven by said actuating means, a clutch-controller adapted to be driven by said means with a differential speed relative to the loose-clutch member, to intermittently effect disengagement 25 of the clutch members and thereby arrest the operation of the back set of rolls, removable transmitting-gearing between the

actuating means and the clutch-controller, and a device to lock the latter from rotation when said transmitting-gearing is removed, where- 30 by a change in the time of the rest and delivery periods of the back set of rolls will be effected.

3. In apparatus of the class described, a set of delivery-rolls, a ratchet rotatable with one 35 of the rolls of the set, a coöperating pawl, a rotatable pawl-carrier loose with relation to said roll and continuously driven, a controller concentric with the pawl-carrier, and having an adjustable cam to intermittently engage 40 said pawl and withdraw it from coöperation with the ratchet, means, including removable transmitting-gearing, to continuously rotate the controller at a slower speed than the pawl-carrier, and a device to hold the controller 45 from rotation when the transmitting-gearing is removed.

In testimony whereof I have signed my name to this specification in the presence of two subscribing witnesses.

ALONZO E. RHOADES.
